ADJUSTABLE RAILROAD CROSSING PLATES

Howard B. Voorhees, 209 E. 4th St., Mishawaka, Ind.

Filed Dec. 6, 1960, Ser. No. 74,077

11 Claims. (Cl. 238—8)

The present invention relates to new and novel adjustable railroad crossing plates, and more particularly to railroad crossing plates which may be more or less universally adjustable and which can be readily adjusted from time to time as necessary.

While the adjustable plate construction of the present invention may be utilized in various applications wherever it is desired to adjust the slope of the flat plate as desired, the invention is particularly adapted for utilization with railway crossings wherein it is desired to fill in the spaces between the tracks and to provide a sort of a ramp means leading from the tracks to the roadway at either side of the tracks.

It is, of course, necessary to provide some sort of a means at the intersection of a railway track with a roadway in order that an automobile passing from one side of the roadway to the other will have a relatively smooth crossing. This can most successfully be accomplished by providing universally adjustable plates formed of steel or the like which can be adjusted both as to elevation and inclination so as to provide the desired finished configuration of the crossing.

In order to accomplish the desired end results, means must be provided whereby relatively heavy steel plates or the like can be manually universally adjusted or in other words it must be possible to raise or lower the various peripheral portions thereof in order to adjust the plate exactly to the terrain and roadway and track positions as may occur. This is accomplished by supporting the plates at spaced points thereof such that it is possible to obtain the desired degree of adjustment, these points of support being preferably adjacent the outer corner portions of the plate. Of course, any number of plates may be employed in adjacent relationship to one another to form the desired surface. In addition, it is often desirable and necessary to readjust the plates from time to time due to varying conditions. Such adjustments should be possible without the necessity of removing the heavy plates from the adjustable support means therefor. Accordingly, the present invention employs a unique arrangement whereby the movable adjusting means thereof is readily accessible from the upper side of the plate supported thereon, and accordingly, the adjustment means may be operated without the necessity of removing the plates therefrom at any time. In addition, it is quite possible that due to the heavy traffic occurring over and adjacent to the plates with the attendant vibrations and jarring which the construction encounters, the adjusting means may be moved from the desired adjusted position. In order to prevent such undesired movement of the adjusting means away from the desired position, a locking means is provided in the form of a plug which effectively prevents relative rotation between the movable adjusting means and the plate means. Since the plate means is supported by a plurality of spaced adjusting means, this positively ensures that the plate will not be moved from its desired adjusted position during operation.

In a further modified form of the invention, a means

2

is provided which positively prevents separation of the adjusting means from the plate means, thereby preventing the plate from being lifted off of the adjustable support means without first utilizing a tool for releasing the movable adjusting means from the associated base means, the base means of course being securely anchored in position on the road bed.

An object of the present invention is to provide an adjustable railroad crossing plate construction including adjusting means supporting each plate at a plurality of points to permit more or less universal adjustment of the plate at a crossing or the like.

Another object of the invention is the provision of an adjustable railroad crossing plate construction wherein the position of the plate may be adjusted while the plates are disposed in operative supported position on the associated adjusting means.

A further object of the invention is to provide an adjustable railroad crossing plate construction including means for locking the plate and its associated adjusting means in operative position.

Still another object of the invention is to provide in an adjustable railroad crossing plate construction means to prevent separation of the plate from its associated adjusting means while at the same time permitting removal of the plate and adjusting means from the shaft base means.

Other objects and many attendant advantages of the present invention will become more apparent when considered in connection with the specification and accompanying drawings, wherein:

Fig. 1 is a perspective view illustrating a railroad crossing formed at the intersection of a railroad track and a roadway;

Fig. 2a is a perspective view of one form of plate means according to the present invention;

Fig. 2b is a perspective view of a modified form of plate configuration;

Fig. 2c is a perspective view of a still further modified form of plate means;

Fig. 3 is a sectional view partially broken away illustrating a portion of the plate means along with the adjusting means associated therewith;

Fig. 4 is a top view of the construction shown in Fig. 3;

Fig. 5 is a sectional view broken away illustrating a modified form of the apparatus;

Fig. 6 is a top view of the modified structure shown in Fig. 5; and

Fig. 7 is a sectional view broken away of a further modified form of the invention.

Referring now to Fig. 1 of the drawings, a railroad crossing is illustrated wherein a railroad track indicated generally by reference numeral 10 includes a pair of spaced rails 11 and 12 which are supported upon conventional ties 13 in a well-known manner. A roadway is illustrated generally by reference numeral 15, and it will be seen that this roadway intersects the railroad track substantially normally thereto as is the conventional arrangement.

In a typical example, the railroad track will be slightly elevated with respect to the roadway and it is desirable to provide some means for providing a ramp from opposite sides of the roadway up to approximately the top level of the rails 11 and 12, and further to provide means substantially spanning the space between the rails so that the wheels of a land vehicle may move smoothly over the railroad tracks as the vehicle traverses the crossing.

According to the present invention, a plurality of adjustable plates 20 are provided for the desired purpose, these plates being of heavy-duty construction and being formed of steel or the like. These plates of course may be arranged in any desired relationship with respect to

one another and as seen in Fig. 1, they are substantially rectangular in configuration, with the longitudinal dimension thereof extending substantially parallel with the rails 11 and 12. The plates may be disposed relatively closely adjacent to one another as illustrated in Fig. 1 so that there will be no large spaces between the plates.

Referring now to Fig. 2a, one of the plates illustrated in Fig. 1 is shown in greater detail, this plate 20 being substantially rectangular in configuration. This type of plate is adapted to be supported preferably adjacent the four corners thereof, and the supporting adjusting means hereinafter more fully described will be disposed directly below the holes 21 formed adjacent the corners of the plate as will hereinafter appear.

Referring now to Fig. 2b, a plate 22 of modified configuration is illustrated, this plate being triangular in configuration. It will be understood that in some railroad crossings, a railroad switching section may be present which will necessitate the provision of odd-shaped plates. In any event, the plates will be so configured as to fit between the various rails on the crossing. When a triangular-shaped plate such as 22 is employed, it is preferably supported adjacent the three corners thereof, and the adjusting supporting means will be disposed directly below the holes 23 formed therethrough.

Fig. 2c illustrates a plate 24 of still further modified form, this plate 24 being similar in configuration to plate 22 with the exception that the apex portion of the triangle has been cut off to thereby form a trapezoidal configuration. Here again, the plate 24 is preferably supported adjacent the corners thereof and the supporting adjusting means may be disposed directly below the holes 25 formed in the plate.

Referring now to Figs. 3 and 4 of the drawings, a first modification of the invention is illustrated wherein for example a plate 20 as shown in Fig. 2a is illustrated, it being understood that the construction is equally applicable to the remaining plates as shown in Figs. 2b and 2c and for that matter to any similar plate means.

As seen particularly in Fig. 3, the hole 21 includes an enlarged portion 21' at the upper portion of the hole and a reduced portion 21'' at the lower portion of the hole thereby defining an annular shoulder 30 therebetween.

It is apparent that hole 21 in plate 20 opens through the upper surface 31 of plate 20. An opposite under surface 32 is provided which is substantially parallel to upper surface 31 and a recess 33 is provided on the under surface 32. Recess 33 includes a portion 34 which is arcuate in shape and actually defines an annular portion which is part of a spherical surface. It will be noted that the lower portion 21'' of the hole through plate 20 opens into the central portion of the surface 34 of the recess in the under surface of the plate.

A suitable support means 40 may assume the form of a body of cement or the like within which are embedded a plurality of anchor bolts 41. The anchor bolts include upper portions 42 which are threaded for attaching the base means of the device securely in position.

The base means 45 is formed of a suitable heavy-duty material such as steel or the like, and comprises a circular lower portion 46 and an upstanding boss 47 formed integral with the central portion of the lower portion 46.

A threaded hole 48 is provided in the central portion of boss 47 and extends completely through the base means for reception of the adjusting means hereinafter described. The lower portion 46 of the base means includes four equally angularly spaced openings 50 through which the upper ends of the anchor bolts 41 extend, the threaded portions 42 of the anchor bolts extending a substantial distance above the lower portion 46 of the base means. Washers 51 are disposed about the anchor bolts, and hex nuts 52 are threaded onto the upper portions 42 of the anchor bolts for firmly securing the base means in operative position as shown particularly in Fig. 3.

The adjusting means is indicated generally by reference numeral 55, the adjusting means including a threaded shank portion 56 which is received within the threaded hole 48 in the base means. Adjusting means 55 also includes an enlarged head 57 having an upper surface 58 which defines a portion of a spherical surface and is complementary to the surface 34 of the recess formed in the plate means. It is evident that the intercooperation between surfaces 58 and 34 permits the plate means to be adjusted angularly with respect to the head 57 and yet at the same time ensures that the plate means will be firmly supported by the adjusting means at all times.

The head means also includes tool-receiving means in the form of an extension 60 which extends upwardly from the central portion of the head and defines a hexagonal outer surface for receiving a socket wrench or the like. It will be noted that extension 60 is of less dimension than a portion 21' of the hole through the plate such that a socket at the end of a socket wrench can be inserted over the extension 60 to thereby turn the adjusting means 55. It is evident that with this construction, the tool may be inserted from the upper surface of the plate means and accordingly, all adjustments which are required will be carried out with plate 20 in place on the adjusting means.

In order to protect the adjusting means and to eliminate tampering therewith to a certain degree, a cover plate 61 is provided which is of substantially disc-like configuration and fits snugly within the enlarged portion 21' of hole 21 and, of course, is seated on the shoulder 30 defined by the hole. A central opening 62 is provided through the cover plate to facilitate withdrawal of the cover plate from the protecting position shown in Fig. 3.

It is evident that with the construction shown in Fig. 3, the elevation of the adjusting means 55 can be readily adjusted from the upper surface of the plate 20, thereby enabling ready adjustment of the vertical height of this portion of the plate 20. At the same time, similar adjustments may be made at other portions of the plate and the spherical surfaces 34 and 58 permit tilting movement of the plate with respect to the various adjusting means such that the plate is firmly supported at each of the adjustment points.

Referring now to Fig. 5, a modified form of the invention is illustrated wherein a plate 70 includes an upper surface 71 and an under surface 72, the under surface 72 having a recess 73 formed therein, this recess including a substantially annular surface 74 defining a portion of a spherical surface.

A hole 75 is formed in the upper surface 71 of the plate, and includes an upper portion 75' and a lower portion 75'' of reduced dimension, the lower portion 75'' being in communication with the central portion of recess 73 in the under surface of the plate.

An annular shoulder 76 is defined between the upper portion 75 of the hole and the lower surface 75'' of the hole.

In this modification, the adjusting means is indicated generally by reference numeral 80 and includes a shank portion 81 which is provided with screw threads on the lower portion thereof (not shown) for the purpose of adjusting the elevation of the adjusting means as in the previous modification. Adjusting means 80 also includes an enlarged head portion 82 having an upper surface 83 which defines a portion of a spherical surface and which is complementary to surface 74 so as to permit ready relative movement therebetween as previously discussed.

A recess 85 is provided in the central portion of surface 83 of the enlarged head 82, the recess 85 extending longitudinally of the adjusting means 80. Recess 85 may be of substantially hexagonal cross-section, but in any event will be non-circular such that it may cooperate with another member to prevent relative rotation therebetween. Recess 85 is adapted to perform a dual func-

tion in this modification, and firstly may receive a correspondingly shaped end wrench which fits snugly within the recess and which may be inserted through the hole formed in the plate to thereby adjust the adjusting means from the upper surface of the plate.

In addition, recess 85 is adapted to receive a portion of a locking means which prevents relative rotation of the adjusting means with respect to the plate as herein-after described.

A locking means as seen in Fig. 5 is indicated by reference numeral 90 and comprises a plug having an upper portion 91 and a lower portion 92 of reduced dimension. Upper portion 91 of the locking means is non-circular and is illustrated as being four-sided. The upper portion 75' of the hole 75 formed in the plate is also four-sided and adapted to snugly receive the upper portion 91 of the locking means to thereby prevent relative rotation between the locking means and the plate. It will be noted that the under surface of the enlarged upper portion 91 of the locking plug means rests upon the annular shoulder 76 formed in hole 75. The lower portion 92 of the locking plug means is also non-circular, and for example, may be hexagonal in cross-section as shown. This hexagonally-shaped portion is snugly received with the correspondingly shaped recess 85 in the head of the adjusting means.

It is accordingly evident that when the locking plug 90 is in operative position as shown in Fig. 5, it will positively prevent rotation of the adjusting means 80 with respect to the plate. This is important since it prevents the adjusting means from rotating and changing its elevation with respect to the base means also. Accordingly, once the various adjustment means associated with the plate 70 are in the proper adjusted positions, the locking plug means 90 may be inserted in operative position thereby ensuring that the movable adjusting elements can not change their adjustment during operation regardless of the vibrations or shock to which the apparatus is subjected.

The upper portion 91 of the locking plug means has a central recess 95 opening through the upper surface of the locking plug, this recess 95 being adapted to receive the tapered end of a tool such that the tapered end can be wedged within the recess to facilitate removal of the locking plug from its operative position. It is evident that after the locking plug has been removed, an end wrench may be inserted within the recess 85 in the head of the adjusting means for adjusting it as desired. It will be apparent that the adjusting means 80 must be positioned such that the portions 91 and 92 are both adapted to register with the portion 75' of hole 75 and the recess 85 in the head of the adjusting means respectively. There are a large number of relative positions of the two elements which will satisfy this requirement, and it is evident that proper registry can be obtained at many different positions.

Referring now to Fig. 7, a further modification of the invention is illustrated, and in this case, a plate 100 is provided with a recess 101 in the under surface thereof, this recess being defined partially within a depending cylindrical boss portion 102 of the plate.

The upper surface portion 103 of recess 101 forms a part of a spherical surface for a purpose similar to that previously described.

An opening 105 is provided through the upper surface of the plate and includes an upper portion 105' and a lower portion 105" of reduced dimension.

An adjusting means 110 is provided and includes a threaded shank 111 adapted to be fitted within a correspondingly threaded hole in a base means. Adjusting means 110 also includes an enlarged head 112 having an upper surface 113 which forms a portion of a spherical surface and is complementary to surface 103 of the recess such that the plate can freely pivot about the head of the adjusting means.

A recess 115 is formed in the enlarged head 112 and opens at the central upper portion thereof, recess 115 being non-circular and shown as hexagonal in cross-section. A locking plug means 120 includes an upper portion 121 and a lower portion 122. As in the previously discussed modification, the upper portion 121 is non-circular and may be square for example and is adapted to fit snugly within the correspondingly square-shaped upper portion 105' of the hole in the plate.

10 Locking means 120 also includes an intermediate portion 125 which is more or less snugly received within the portion 105" of the hole, these portions being shown as substantially cylindrical.

The lower portion 122 of the locking means is non-circular and may also be hexagonal in cross-section and is adapted to fit snugly within the corresponding recess formed in the head of the adjusting means. It is evident that the locking means 120 serves to prevent relative rotation between the adjusting means and associated plate.

20 As in the previous example, a recess 126 is formed in the upper portion 121 of the locking means and opens through the upper surface thereof for receiving a tapered end of a tool for assisting in removal of the locking means from operative position.

25 Just below the enlarged head portion 112 of the adjusting means, a portion 130 is provided which includes an outer surface 131 forming a portion of a spherical surface.

A ring means 135 of substantially annular configuration is fitted within the lower portion of the recess 101 in the plate, and may be suitably affixed thereto as by welding as indicated by reference numeral 136. Ring means 135 also includes an annular surface 138 which forms a portion of a spherical surface and which is complementary to the outer end 131 formed on portion 130 of the adjusting means.

The surface 113 formed on the upper part of the enlarged head of the adjusting means and the surface 131 formed on portion 130 of the adjusting means define portions of two spherical surfaces, each of which has a common center lying at the point indicated by letter C. By so forming the surfaces about a common center, unrestricted tilting movement of the plate with respect to the adjusting means is obtained.

45 It is evident that the modification shown in Fig. 7 will operate in substantially the same manner as that shown in Fig. 5 with the exception that the ring means 135 positively prevents separation of the plate from the adjusting means which, of course, can occur in the modification shown either in Fig. 3 or Fig. 5.

It is apparent from the foregoing that there is provided a new and novel adjustable railroad crossing plate construction wherein a plate is associated with adjusting means for supporting the plate at a plurality of points thereby permitting substantially universal adjustment of the plate as employed at railroad crossings and the like. In each of the modifications of the invention, the adjusting means can be adjusted while the plate is in operative position by the provision of holes formed through the

60 plates and also by the provision of tool-receiving means on the heads of the adjusting means either in the form of an extension or a recess. Means is also provided in certain of the modifications for positively locking the adjusting means in position and preventing relative rotation between the adjusting means and the plate. In the modification shown in Fig. 7, means is further provided for positively preventing separation of the plate means from the adjusting means.

As this invention may be embodied in several forms 70 without departing from the spirit or essential characteristics thereof, the present embodiment is therefore illustrative and not restrictive, and since the scope of the invention is defined by the appended claims, all changes that fall within the metes and bounds of the claims or that 75 form their functional as well as conjointly cooperative

equivalents are therefore intended to be embraced by those claims.

I claim:

1. In an adjustable railroad crossing plate construction, a plate means including an upper surface and an under surface, a recess formed in said under surface, a hole formed in said upper surface and being in communication with said recess, a base means, and a movable adjusting means adjustably mounted in said base means, said movable adjusting means including a head portion received within said recess in said plate means for supporting said plate means on said adjusting means, said head means including tool-receiving means whereby a tool can be inserted through the hole in said plate means for adjustment of the movable adjusting means while the plate is supported on the movable adjusting means.

2. In an adjustable railroad crossing plate construction, a plate means having an upper surface and an under surface, said under surface having a recess formed therein, a portion of said recess defining a portion of a cylindrical surface, said upper surface having a hole formed therein and being in communication with said recess, a base means having a threaded hole formed therein, and a movable adjusting means including a shank portion and a head portion, said shank portion being threaded for reception in said threaded hole in the base means, said head portion being received within said recess and including a portion defining a portion of a spherical surface and being complementary to the spherical surface portion of the recess, said head including tool-receiving means on the outer portion thereof for receiving a tool extending through the hole in said plate means.

3. Apparatus as defined in claim 2, wherein said tool-receiving means comprises a non-cylindrical extension extending outwardly of the head and of less dimension than said hole whereby a tool may be extended through the hole and around said extension.

4. Apparatus as defined in claim 2, wherein said tool-receiving means comprises a non-cylindrical hole formed in said head and opening outwardly of said head for receiving a tool therein and also being adapted to receive a locking plug means therein.

5. In an adjustable railroad crossing plate construction, a plate means having an upper surface and an under surface, a recess formed in said under surface and including a portion defining a portion of a spherical surface, said plate means having a hole formed therethrough opening through said upper surface and being in communication with said recess and of less dimension than said recess, a base means, means for firmly anchoring said base means in operative position, said base means having a threaded hole formed therein, movable adjusting means including a threaded shank portion and an enlarged head portion, said threaded shank portion being threaded within said threaded hole, whereby relative rotation of said adjusting means produces axial movement of said adjusting means, said enlarged head portion including a portion defining a portion of a spherical surface and being complementary to the portion of the recess defining a portion of a spherical surface whereby said plate means may freely pivot about said enlarged head portion, said enlarged head portion including tool-receiving means accessible through the hole in said plate means for rotating said movable adjusting means with respect to said base means while the plate means is supported on said enlarged head portion of the adjusting means.

6. Apparatus as defined in claim 5, wherein said tool-receiving means comprises an extension extending longitudinally of said adjusting means from the enlarged head thereof and being of non-cylindrical configuration, the extension being disposed within said hole and of less dimension than said hole for receiving a tool extending through said hole and in surrounding relationship to the extension.

7. Apparatus as defined in claim 6, wherein said plate

means defines a shoulder about the upper portion of said hole, and a cover plate disposed in overlying relationship to said hole and supported on said shoulder.

8. In an adjustable railroad crossing plate construction, a plate means having an upper surface and an under surface, a recess formed in said under surface and including a portion defining a portion of a spherical surface, said plate means having a hole formed therethrough opening through said upper surface and being in communication with said recess and of less dimension than said recess, a base means, means for firmly anchoring said base means in operative position, said base means having a threaded hole formed therein, movable adjusting means including a threaded shank portion and an enlarged head portion, said threaded shank portion being threaded within said threaded hole, whereby relative rotation of said adjusting means produces axial movement of said adjusting means, said enlarged head portion including a portion defining a portion of a spherical surface and being complementary to the portion of the recess defining a portion of a spherical surface whereby said plate means may freely pivot about said enlarged head portion, said enlarged head portion including tool-receiving means accessible through the hole in said plate means for rotating said movable adjusting means with respect to said base means while the plate means is supported on said enlarged head portion of the adjusting means, said tool-receiving means comprising a non-cylindrical recess formed in said enlarged head and opening toward said hole for receiving a complementally shaped tool therein.

9. Apparatus as defined in claim 8, wherein said hole formed in said plate means is of non-cylindrical configuration, and a locking plug means including a lower portion and an upper portion, said lower portion being of complementary configuration to and snugly receivable within the tool-receiving recess of said adjusting means, and the upper portion of said locking plug means being of complementary shape to and snugly received within the hole formed in said plate means such that when the locking plug means is disposed in operative position with the lower portion disposed within the recess in the head portion of the adjusting means and with the upper portion thereof received within the hole of the plate means, the locking plug means positively prevents relative rotation between the adjusting means and plate means.

10. Apparatus as defined in claim 9, wherein the upper portion of said locking plug means has a hole formed therein and facing toward the outer end thereof for receiving a member to facilitate removal of the locking plug from its operative locking position.

11. In an adjustable railroad crossing plate construction, a plate means having an upper surface and an under surface, a recess formed in said under surface and including a portion defining a portion of a spherical surface, said plate means having a hole formed therethrough opening through said upper surface and being in communication with said recess and of less dimension than said recess, a base means, means for firmly anchoring said base means in operative position, said base means having a threaded hole formed therein, movable adjusting means including a threaded shank portion and an enlarged head portion, said threaded shank portion being threaded within said threaded hole, whereby relative rotation of said adjusting means produces axial movement of said adjusting means, said enlarged head portion including a portion defining a portion of a spherical surface and being complementary to the portion of the recess defining a portion of a spherical surface whereby said plate means may freely pivot about said enlarged head portion, said enlarged head portion including tool-receiving means accessible through the hole in said plate means for rotating said movable adjusting means with respect to said base means while the plate means is supported on said enlarged head portion of the adjusting means, said enlarged head portion also including a second portion defining a portion of a

spherical surface and being oppositely disposed to said first-mentioned spherical portion thereof, and ring means fixed to said plate means and disposed in surrounding relationship to the lower part of said enlarged head portion, said ring means including an annular bearing surface forming a portion of a spherical surface and being complementary to said second portion of the enlarged head portion and receiving said second portion of the enlarged head portion thereon whereby separation of the

adjusting means from the plate means is positively prevented.
